UNITED STATES PATENT OFFICE.

JAMES FRANKLIN FELLOWS, OF TROY, NEW YORK, ASSIGNOR TO FELLOWS & CO., OF SAME PLACE.

CUFF.

SPECIFICATION forming part of Letters Patent No. 611,241, dated September 27, 1898.

Application filed October 24, 1896. Serial No. 609,953. (No model.)

To all whom it may concern:

Be it known that I, JAMES FRANKLIN FELLOWS, a citizen of the United States, residing at Troy, county of Rensselaer, and State of New York, have invented certain new and useful Improvements in Cuffs, of which the following is a specification.

The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in both figures.

Figure 1 of the drawings is an end view of my improved cuff attached to the wristband 20 of a shirt in position for use. Fig. 2 is a plan view of the inner side of the cuff, showing the cuff laid out flat with the attaching-tab bent upwardly at an angle to the body part of the cuff.

My invention relates more particularly to that class of detachable cuffs known as "link-cuffs," and consists of a cuff having an attaching-tab secured to the cuff a short distance from one end and on its inner surface.

The object of the invention is to give to both ends of the cuff when in use a similar and poke effect and to increase the effective depth or width of a double or reversible cuff.

A represents the body part of an ordinary 35 detachable double or reversible cuff, having the buttonholes A' in each corner to receive the link buttons B B, by which the ends of the cuff are held together when in use.

The tab C is secured to the body part of 40 the cuff by the lines of stitching C'. The tab is provided in its loose or fly end with a pair of buttonholes C², adapted to receive the button D on the wristband D' of a shirt. The shirt is not shown.

When one end of the cuff-body is first but-

toned onto the shirt-button and the other end of the cuff-body afterward buttoned onto the same button, as commonly practiced, one end of the cuff laps the other just the same as one end of the wristband D' is shownlapping the other end in Fig. 1, and the ends would not project outwardly side by side to give the "poke" effect, as shown in Fig. 1.

By having the tab secured to the inner surface of the cuff and so as not to project beyond the side edges of the cuff the tab when the cuff is in use is wholly concealed from view within the cuff and does not project at any point to catch the overlying coat-sleeve and prevent the latter when accidentally drawn up from resuming its normal position relatively to the cuff.

I preferably secure one end of the cuff to the wristband by passing the shirt-button through a buttonhole E in the body of the 65 cuff, the other end being secured by inserting the same button through a buttonhole C² in the attaching-tab.

The buttonhole E may be located at any point within the adjacent end edge line of 70 the cuff. This arrangement enables me to bring the ends of the cuff nearer together in use than would be possible if both ends of the cuff were provided with attaching-tabs.

What I claim as new, and desire to secure 75 by Letters Patent, is—

A detachable link-cuff, provided near one end with a buttonhole-tab secured to the inner face thereof at a point slightly remote from one end of the cuff and projecting beyond the same, with a buttonhole in the projecting end of the tab and having in the opposite end of the cuff-body a corresponding buttonhole, substantially as described.

In testimony whereof I have hereunto set 85 my hand this 12th day of October, 1896.

JAMES FRANKLIN FELLOWS.
